UNITED STATES PATENT OFFICE.

LEO PRANGE, OF BROOKLYN, NEW YORK.

DESIGN FOR A BUTTON.

SPECIFICATION forming part of Design No. 21,323, dated January 26, 1892.

Application filed December 18, 1891. Serial No. 415,557. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises an elliptical or ellipsoidal figure extending across a button. It is 15 shown as composed of a central group of jewel-like figures a' , arc-shaped lines a^2 , representing rope or cord and located outside of the jewel-like figure a' , and arc-shaped rows of jewel-like figures a^3 , arranged outside the lines

a^2 . At the extremities of the arc-shaped rows 20 of jewel-like figures a^3 are large jewel-like figures a^4 , and at the sides of these jewel-like figures a^4 are lozenge-shaped jewel-like figures a^5 . Between the lozenge-shaped jewel-like figures a^5 , at each end of the elliptical figure A, are 25 border-lines B, representing cord or rope.

What I claim, and desire to secure by Letters Patent, is—

The design for a button, as herein shown and described.

In testimony whereof I have signed my name to this specification in the presence of two subscribing witnesses.

LEO PRANGE.
